UNITED STATES PATENT OFFICE

2,139,899

DEPTH MEASURING DEVICE FOR OIL WELL EQUIPMENT

Frank L. Le Bus, Oklahoma City, Okla.

Application December 4, 1936, Serial No. 114,141

2 Claims. (Cl. 33—126.5)

This invention relates to improvements in well drilling appliances generally and more particularly to a type of the same for facilitating the lowering of a drill pipe string downwardly in the bore of a well, and for measuring the depth of the hole, without removal from the drill pipe string.

The present invention further relates to a well drilling appliance covered by Letters Patent No. 10 1,871,536, issued to the applicant August 16, 1932. In said patent the appliance consists of a novel valve construction adapted to lessen the strain on the well rig cable and the drum brakes, obtained by the closing of the valve, brought about 15 by the pressure of up-flow of water and the like when the pipe string is lowered in the well bore and thereby tending to float the pipe string and relieve the strain referred to. The valve also has 20 for an object to permit the passage of an explosive charge below the valve to loosen a stuck drill bit or pipe string section.

In said former Patent No. 1,871,536 the tubular valve body to which the valve is swingably attached and under pressure and stress, frequently 25 becomes loose, moving slightly upwardly or downwardly.

It is therefore one of the objects of this invention to provide means to stop leakage around the tubular valve body during such movements, by 30 a change in and addition to the structure embodied in said appliance.

Another object of the invention is the provision of means for opening and closing said valve from a point above the ground surface or at the well 35 rig for the purpose of ascertaining the depth of the hole being drilled and this without the removal of the operative valve. In this mode of operation the pipe string with the valve arrangement can be floated in the manner heretofore explained and a plumb bob and measuring line can 40 be passed through the string of drill pipe and through the valve down to the top of the drill bit. After such measurement has been made, the measuring line can be withdrawn through the 45 valve. In the meantime, the valve itself has been held open for the downward and upward passage of the measuring line by a device forming part of the improvement and hereinafter described in detail. The valve then closes and is again ready 50 for further drilling operations.

It is the common practice in well boring to place the ordinary float valve at various points in the string of pipe and heretofore in order to get a measurement of the depth of the well bore, 55 some type of float valves must be left out of the

drill pipe string and the operator must take a chance without benefit of the float valve. In the present invention the valve can be opened by the device referred to above in connection with the measuring line and held open until the depth is ascertained, after which the removal of the device releases the valve and causes it to close.

With the preceding and other objects in view, the invention will be readily understood from a perusal of the following detailed description, taken in connection with the accompanying drawing, forming a part of this specification, and in said drawing:

Figure 1 is a vertical and longitudinal sectional view of the pipe sections, showing the valve in open position and illustrating one form of means for opening the valve by a depth measuring element.

Figure 2 is a view similar to Figure 1, showing the valve in open position and held in said position by another form of depth-measuring means,

Figure 3 is an elevational view in vertical position of the valve opener and depth measuring means per se as shown in Figure 1,

Figure 4 is an elevational view of the valve opener per se as shown in Figure 2,

Figure 5 is a plan view of a ring employed to prevent leakage around the tubular valve body.

Referring in detail to the drawing, and wherein like parts will carry like indicating characters, the pipe section 1 is interiorly threaded at 2 and has also outward threads as at 3 for connection to a string of pipe 4 and a drill head 5 of well known construction. Likewise the valve 6, lugs 7 and 8 and spring 9 are merely shown for the sake of making clear the invention, said parts being covered in said former patent referred to.

Disposed within the pipe section 1 is a tubular body 10 which is cut away as shown to provide an angular seating surface for the valve 6—also covered in said former patent.

Experience has developed the fact that the valve body 10 tends to move or slip upwardly or downwardly of the interior of the pipe section 1, due to stress and strain in the operation of the appliance, and to prevent this leakage the outer periphery of the tubular valve body 10 is in this invention provided with an annularly grooved recess to receive the steel rings 11, one of said rings being shown by itself in Figure 8. A gasket 12 or rubber packing element is placed around the tubular valve body 10 and the rings 11 are then put in position, one at the top and one at the bottom of the gasket or packing element 12.

These rings are made or cut in half sections and each section is slipped or forced upon the valve body in the recess and then welded as shown at 13, Figure 8. As a further aid in holding the tubular valve body in position, an annular rim 14 is formed on the interior of the section 1 and the tubular valve body 10 is reduced in diameter below the lowermost ring 11. This reduction in diameter of the valve body 10 thus provides an annular shoulder 15 and prevents the valve body from movement in one direction. The lower end of the drill stem 4 prevents movement in the other direction.

In order to provide for measuring the depth of the well bore or hole being drilled, one end of the tubular body 10 is bevelled as shown at 16 to seat the annular lip 17 of a valve opener. As shown in Figure 4 this valve opener is hollow and its lower end 18 is thickened to provide weight and stability. The body 19a is cylindrical to enable it to snugly engage for the most part with the inner walls of the tubular body 10. This permits the annular lip 17 to seat upon the bevelled portion 16 of the tubular body—clearly shown in Figure 4. One end of the valve opener is conical shaped having a neck 19 and each end is apertured as at 20 and 21 for the passage of a small cable or plumb bob line 23. One end of this line carries a plumb bob 24.

Another form of valve opener is shown in Figure 7. This form consists of a hollow body 25, open at both ends. One end of this form is reduced in diameter as at 26 and the opposite end is formed into an annular lip 27.

The operation of the valve opener is as follows: The valve opener shown in Figures 4 and 6 is seated on the plumb bob line 23 and held in position by the plumb bob 24. It is then lowered into the drill pipe string. As the valve opener comes in contact with the valve 6, the downward movement of the valve opener will shove the valve 6 aside in the position shown and the lip 17 will be seated upon the bevelled surface 16 of the valve body 10, thus holding the valve open. The plumb bob and plumb bob line then continue the descent to the bottom of the hole or to a point on top of the drill bit and the depth of the hole is determined. When the end of the descent is reached, the plumb bob and line are withdrawn upwardly until the bob 24 is received again in the notch 21—whereupon the valve opener is withdrawn, allowing the valve to again close.

In the form of valve opener shown in Figures 5 and 7 the valve opener 25 is dropped into

the pipe string from the well rig or ground surface and the impact forces the valve 6 to open position as shown in Figure 5, the lip 27 being supported upon the bevelled surface 16 of the valve body. The plumb bob line 23 and the bob 24 are then lowered to ascertain the depth or bottom of the hole as before, and then withdrawn, and the valve opener left in the pipe string. The valve opener is later removed when the pipe string is pulled, by the removal of the upper pipe string section 4.

While the drawing and description illustrate and describe a practical working embodiment of the invention, it is obvious that alterations and changes may be made therein, without departing from the spirit and intent thereof and within the scope and meaning of the appended claims.

What is claimed as new is:

1. In combination with a floating valve structure for drill pipe lines in well boring, a device for engaging the interior of said valve structure to open said valve and for maintaining said valve in open position and for ascertaining the well depth, said device comprising a hollow cylindrical body, adapted to be seated within said valve structure, there being openings in both ends of said hollow cylindrical body, a cable or line passing through said body, a weight carried on one end of the cable or line, said cylindrical body adapted to be lowered into the well to open the valve of the valve structure and hold it open, the weighted end of the cable descending to ascertain the well depth and picking up said cylindrical body on ascent and thereby closing said valve.

2. In combination with a floating valve structure for drill pipe lines in well boring, a device for engaging the interior of said valve structure to open said valve and for maintaining said valve in open position and for ascertaining the well depth, said device comprising a hollow cylindrical body adapted to engage with and seat within said valve structure said body converging at one end to form a conical neck, an annular overhanging lip projecting outwardly from the body next and below said conical neck, the opposite end of said body being thickened to accentuate the weight of the body, there being an opening in said neck and said thickened portion of the body, a cable or line passing through said openings and through said body, and a weight attached to one end of the cable or line.
